RECESSED SOAP HOLDER

James R. Turek, Johnstown, Pa., and Eugene C. Petrie, Elmhurst, and Robert B. Attridge, Evergreen Park, Ill., assignors to Crane Co., Chicago, Ill., a corporation of Illinois

Filed Apr. 20, 1960, Ser. No. 23,398
3 Claims. (Cl. 45—28)

This invention relates generally to bathroom trimmings accessory to bathtub, lavatory, and closet bowl installations. More particularly, it is concerned with the type of trimmings ordinarily identified as a soap holder or a tumbler holder.

In order to have a better appreciation of the advantages of this particular contribution, it should be understood in most cases soap holders, or tumbler holders, on occasion are provided with a removable supporting insert member generally made of plastic, glass, metal, or other suitable materials, the purpose obviously being to allow for ease in maintaining a sanitary condition within the recesses of the said holder. In this connection, it is of course desirable also that such insert member be not only firmly positioned during use against both lateral as well as longitudinal movement in relation to the floor or base of the recessed holder, but also that the said supporting insert member may be easily removed without requiring special tools. Further, it should be easily and conveniently replaced by the average home owner or tenant or other householder.

It is therefore one of the more important objects of the present invention to provide a bathroom fixture of the type hereinafter described in which the insert member by the relatively simple maneuver of lifting and/or tilting the insert member upwardly, permits of the said insert to be easily removed. Also, by an opposite entry approach from the forward and open end of the soap holder housing the said insert member may be installed by sliding it inwardly relative to the housing base. After a limited degree of such movement inwardly to bear against a rear wall defining the inner limits of the housing the insert member may then be permitted to move in a direction arcuately toward the base or floor of the housing and engage a button or pin, the latter positively or frictionally engaging a groove or recess provided on an upturned wall surface either inwardly or outwardly of the insert.

A further object is to provide for a composition, plastic or metal tray or holder in which by predetermined sliding movement relative to the housing opening the insert can be securely attached thereto at either a rear portion of the housing or at side portions thereof.

A further object is to provide for a fixture of the character hereinabove referred to in which a semi-concealed pin or button is provided in the back of the housing or on the side walls of the housing whereby to positively or frictionally hold the said insert member in place.

A further object is to provide for an insert member in which the attachment arrangement therefor permits of the employment of a close-fitting insert or soap holder tray in the housing and thus results in a more sanitary assembly with the housing.

A further object is to provide for a bathroom soap holder construction in which simple, economical and positive retention means and easy removability are conveniently provided.

Other objects and advantages will become more readily apparent upon proceeding with the following description read in light of the accompanying drawings, in which

FIG. 1 is a side exterior view of a soap-or tumbler-holder embodying our invention;

2

FIG. 2 is a side exterior view of the said holder embodying our invention;

FIGS. 3 and 4 are fragmentary sectional views taken on the lines 3—3 and 4—4 respectively of FIG. 2;

FIG. 4a is a magnified view of the insert attaching means employed in FIG. 4;

FIGS. 5, 6 and 7 are views of a modified form of our invention; and

FIGS. 8 and 9 are of side and plan sectional views respectively of a further modified form of the invention.

Similar reference numerals refer to similar parts throughout the several views.

Reference is now made to FIG. 1. A soap holder or tumbler holder housing 1 is shown which may be made either of sheet metal, plastic, or other suitable composition. It comprises a frame of generally rectangular configuration as shown at 2. The housing 1 at its rear portion as at 3 is of generally semi-cylindrical recessed configuration, although the form of the latter is not particularly significant. It will be understood that the housing 1 is formed so as to be mounted within a suitably formed recess or hole in the wall of a bathroom or the like, the engaging edges indicated at 4 of the frame making abutting contact preferably with the face of the bathroom wall so as to thereby conceal the otherwise rough hewn and unsightly edges of the wall opening. For purpose of attachment to the wall as indicated at 5 and 6, the rear wall portion of the opening 3 of the housing 1 may be suitably secured to construction headers (not shown) by means of nails or screws or the like (also not shown) and with the frame firmly positioned with its surface 4 against the vertical wall surface of the room in which it is installed.

The removable insert member generally designated 7 (FIG. 3) serves as the carrier or support for either soap or a tumbler. The usual ribs 40 serve as contacts for the soap or tumbler. The novel means of attachment of the insert to the housing 1 forms the subject matter of this invention.

At the rear portion of the semi-circular portion 3 of the housing, a means of attachment of preferably a half-bolt construction, generally designated 8, is attached by means of a peened over form or rivet form of connection, as at 9. It will be noted that the lower half of the bolt head 11 extends downwardly after predetermined inward movement of the insert member 7 to the position illustrated. It is then mounted within the recess 12 for suitable engagement therewith as indicated more clearly in the enlarged view shown in FIG. 4a. Initially being relatively loosely received therewithin and with a sufficient clearance between the pin or button-head 8 and the recess 12, it allows for the insert member to be inserted (and removed) when the insert assumes the position and in the manner indicated by the dotted lines shown in FIG. 4. In the latter position, it will be noted that the insert inner corner portion 13 serves as the bearing or pivot point when the insert 7 is tilted upwardly in being removed (or mounted) and allows for the easy removal (or assembly) within the housing of the said insert member from or upon the floor or base 10. At its forward portion, the insert 7 as shown more clearly at 14 is provided with a downwardly extending flange whereby to assist in obtaining a grip upon said forward portion of the insert when the latter is being positioned within the housing recess 3 as hereinabove described.

As shown more clearly in the transverse plan sectional view of FIG. 3, the insert member 7 fits relatively snugly on its peripheral portion primarily for the purpose of providing a tight juncture therewith and therefore providing greater sanitation. In the latter connection, it will be noted that preferably the upstanding peripherally curved wall 15 of the insert member 7 being preferably made of

resilient material is tapered and sprung slightly outwardly. Thus, as more clearly shown in FIG. 2, a peripheral line engagement as at 16 is effected with the semi-circular surface 3 of the housing opening. The immediately described structural provision accordingly permits the insert wall 15 to function in a limitedly resilient manner. By reason of such resilient structure and the engagement with the semi-cylindrical surfaces 3, the insert bolt head on its rounded surface 17 initially engages the recess at 18, as shown more clearly in FIG. 4a. The over-all effect is to assure greater stability and firmness of fit in the positioning of the insert member. At the same time, there is thus an allowance for slight resilient displacement of the insert wall 15 outwardly when the insert upper edge 18 of the recess 12 contacts the slightly rounded area defined by the surface 19 of the bolt 8. Such contact will take place immediately upon positioning the insert member 7 within the housing, which is shown in FIG. 4, and then takes the final position shown more clearly in FIG. 4a. It has been found that such structure with its resiliency eliminates prior objectionable breakage at such location, and it also provides a nice easily attained adjustment to result in the desired secure assembly of the insert within the said soap holder housing.

There has accordingly been provided an insert retaining structure capable not only of holding the insert firmly against relative movement, but it also permits the insert to be easily installed and removed.

A further modified form of attachment may be used to obtain a similar beneficial result in which side portions instead of the rear or inward portion of the insert 7 may be used to effect the attachment of the said member.

As shown more clearly in FIG. 5, the side disposed pins 21 are mounted so that the inner portions thereof as at 22 extending through the wall of the housing 1 engage the vertically disposed slots 23. The detailed construction of the slot 23 is more clearly set forth in the fragmentary section in FIG. 7, the slot being inwardly tapered as indicated at 20 so as to provide the slot lower widened portion as at the open end 24. Thus, it will be apparent that the oppositely disposed slots 23 extend downwardly preferably to the base surface 10 of the housing and upon which surface the said insert member is supported, the slots terminating with said open end. In this modified construction, as distinguished from that shown in FIG. 4, in installing the insert member it is simply slipped over the inner end portions of buttons or pins so that the oppositely disposed slots 23 correspond with the pins 21. Therefore, by simply moving the entire insert member 7 downwardly in a direction toward the housing base or floor 10, the insert is placed firmly and securely in position and thereby held against accidental removal. In this construction, it will likewise be appreciated that the upper outer edge of the insert as indicated at 16 of the wall 15 of the insert 7 bears securely and in substantially fluid-tight relation against the inner periphery of the semi-cylindrical surface 3 to encourage the easy maintenance of a sanitary condition. Specifically, soap suds, water, and the like are effectively prevented from entering upon the surface 3 behind the insert wall 15. It has been found that this arrangement also keeps the screws or bolts 16 from being adversely affected by moisture to cause corrosion or rusting, and so forth, otherwise resulting if a tight joint is not provided between the insert 7 and the housing surface 3.

In FIGS. 8 and 9, a still further modified form of insert means of attachment to the soap-holder housing is illustrated. In this structure, the insert member generally designated 7 is provided on its outer periphery at oppositely disposed side portions thereof with an angular form of groove or slot 25, and having upwardly extending vertical slotted portion 26 which in the final positioning of the insert 7 fits over the inwardly projecting pin 21 on each side thereof as shown more clearly in FIG.

8. In this modification, it is to be noted that for the purpose of frictionally holding the insert member 7 firmly in the housing 1, each of the oppositely disposed slotted portions 25 is provided with the surface 27 which in extending arcuately inwardly slightly functions as a cam-like configuration. Thus, the pins 21 as they initially enter the horizontal slot 25 will follow a radius departing from that defining the insert outer surface 15. Therefore, as the insert member is moved inwardly toward the surface 3 of the housing 1, each of the surfaces 27 of the grooves will frictionally or slidably engage the inner end surface portions 28 of the pins 21. The latter members are riveted firmly in place in a manner similar to that described in connection with the other figures. The overall effect of the said frictional engagement between the surface 27 of the insert member and the inner end surface 28 of the pin 21 is to function substantially in the same manner as the pitched vertical surface 20 of FIG. 7 when the insert member is finally positioned firmly in place on the housing floor or base 10.

In this construction, it will also be understood that the insert member 7 when being assembled within the holder housing 1 is tipped slightly upwardly so that its lower corner surface 13 serves as the sliding contact pivot point during such time as the pins 21 are moving in the slot portion 27 toward the portion 26. The ultimate connection as the pins 21 enter the latter slot portion to engage the pin end surface 28 provides the assurance of a tight and sanitary juncture between the said inner surface 3 of the housing and the upper peripheral wall surface 15 of the insert member 7.

In other respects, the operation of the modified forms follows the general principle of securement described in the first mentioned figures.

It will be clear that the embodiments here illustrative of the invention are relatively economical and simple in construction, and provide an ease of installation or removal with respect to the insert member from the said housing that is highly desirable.

It will also be apparent that although several embodiments of the invention have been shown, many other changes in construction may be made without departing from the scope of the invention as set forth in the following claims.

We claim:

1. A soap holder or the like for mounting in a wall opening, said holder having a housing with a base and defined at a forward portion thereof with a marginal frame and an opening extending rearwardly of the frame, a pin mounted on a wall defining a rear limit of the opening within said frame of the housing, the pin having a head, the underside of the head being tapered and spaced from said opening rear limit, a soap supporting insert for entering and conforming with the base, the said insert having a rear wall substantially conforming with the wall defining said rear limit of the housing opening, the said rear wall of the insert being formed with a socket, the upper portion thereof being suitably cut away to closely engage a shoulder portion of said pin formed by said tapered underside of the head whereby to maintain the said insert against substantial endwise movement relative to the said housing base, an outer peripheral portion of the said insert at this stage of its positioning on the base being snugly drawn against inner wall surfaces defining the said opening to form a relatively tight joint therebetween.

2. A recessed soap holder for mounting in a wall opening, said holder having a housing with a base and defined at a forward portion thereof with a marginal frame and an opening within the frame rearwardly thereof, a pin mounted on a rounded wall defining a rear limit of the opening within said frame of the housing, the said pin having a head portion spaced from the rounded wall, a soap supporting insert for entering and conforming with the base, the said insert having a rear wall conforming

ing with the rounded wall defining said rear limit of the housing opening, an upper surface on the rear wall portion of the insert being relieved at an upper portion thereof, the head portion of said pin being downwardly tapered on an inner transverse edge for engaging an inner vertically extending surface of the upper relieved portion of the insert to retain the said insert against substantial endwise movement relative to the said housing base, at least an outer arcuate portion of the insert bearing snugly against an inner annular portion of the rounded wall defining the opening within the frame and rearwardly thereof.

3. A soap holder for mounting in a wall opening, said holder having a housing with a base and defined at a forward portion thereof with a marginal frame and an opening within the frame, a pin mounted on a wall defining a rear limit of the opening within said frame of

the housing, the pin having a head portion in spaced relation to said wall defining the rear limit of said opening, a soap supporting insert for entering and conforming with the base, the said insert having a rear wall forming with the wall defining said rear limit of the housing opening, the said rear wall of the insert being relieved at an upper portion thereof and of inverted T-configuration when viewed in plan and engaging an inner end downwardly tapered portion of said pin head to retain the insert against substantial endwise movement relative to the said housing.
